UNITED STATES PATENT OFFICE

107,854

DESIGN FOR A COMBINED GRAVY BOAT AND TRAY

Minn S. Cornell, Jr., Middletown, Conn., assignor, by mesne assignments, to The Middletown
Silver Company

Application July 13, 1937, Serial No. 70,387

Term of patent 7 years

To all whom it may concern:

Be it known that I, Minn S. Cornell, Jr., a citizen of the United States, residing at Middletown, in the county of Middlesex and State of Connecticut, have invented, a new, original, and ornamental Design for a Combined Gravy Boat and Tray, of which the following is a specification, reference being had to the accompanying drawing, forming part thereof.

Figure 1 is a side elevational view of the combined gravy boat and tray illustrated partly in section, showing my new design; and

I claim:

The ornamental design for a combined gravy boat and tray as shown and described.

MINN S. CORNELL, JR.
